TOY WATER PISTOL

Arthur A. Lange, Summit, N.J. (½ Park Plastics Co.,
940 Park Ave., Linden, N.J.)
Filed Apr. 10, 1962, Ser. No. 186,410
9 Claims. (Cl. 222—79)

My invention relates to a water pistol, and more particularly to a water pistol that is formed by the placing together of two complementary parts formed of suitable plastic material. When the two complementary parts are placed together, they hold in assembled position a small pump that is trigger-actuated for propelling water from the pistol outwardly through the barrel of the pistol, as those skilled in the art will fully appreciate.

As a feature of my invention, I so form the two complementary and opposed parts of my pistol that when they are assembled to one another, there is formed in the barrel portion of the completed pistol an internal passageway spaced from the peripheral surface of each of the two opposed parts. By so forming the passageway, any leaks that occur in the passageway permit the flow of fluid back to the main interior chamber of the pistol, instead of outwardly of the pistol, as is usual in prior art constructions.

As a further feature of the invention, I form one of the complementary opposed parts of the pistol of my invention with a rib extending transversely therefrom for interlocking engagement with the other part through entry into a groove in the other part. This rib is at the outer end of the barrel portion of its particular part, so that not only will the rib assist in holding the two parts of the pistol in assembled relation, but it also functions as the nozzle through which water will be pumped out of the pistol.

As a still further feature of my invention, I form the outer configuration of the parts of my pistol to simulate the appearance of a genuine pistol, while simultaneously providing thereby for the saving of material and the shaping of the interior parts of the pistol, all as will be made clear presently.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims be regarded as including such equivalent constructions as do not depart from the spirit and scope of my invention, in order to prevent the appropriation of my invention by those skilled in the art.

Referring now to the drawings:

FIG. 1 is a perspective view of the water pistol of my invention showing the opposed complementary parts thereof assembled to one another to form a complete pistol;

FIG. 2 is a plan view of the interior of one of the parts, showing the trigger-actuated pump applied thereto;

FIG. 3 is a plan view of the interior of the other of the two complementary parts;

FIG. 4 is a section taken along lines 4—4 of FIG. 2, but with the part of FIG. 3 assembled to the part of FIG. 2;

FIG. 5 is a section of FIG. 2, but also with the part of FIG. 3 applied in assembled relation to the part of FIG. 2;

FIG. 6 is a partial section and exploded view of the two end portions of the parts of my pistol just prior to the assembly thereof; and

2

FIG. 7 is a section taken along the line 7—7 of the part of FIG. 2 after the part of FIG. 3 has been applied thereto.

Referring now more particularly to the drawings, reference numeral 10 designates in FIG. 2 one of the complementary parts used to form the pistol of my invention. Reference numeral 11 designates in FIG. 3 the other of the two complementary parts. The part 10 is formed with a substantially continuous peripheral surface, designated by reference numeral 12, having a series of dowel pins 13 formed integrally therewith. This substantially continuous surface 12 has a semi-circular depressed portion 14 and a second semi-circular depressed portion 15.

The part 11 has also a substantially continuous surface 12a formed with a series of dowel accepting depressions 13a. The continuous surface 12a has a semi-circular opening 14a, and a second semi-circular opening 15a. It is quite obvious that when the two parts 10 and 11 are placed with their surfaces 12 and 12a in contact, the dowels 13 will enter the series of dowel depressions 13a. It is further obvious that the two parts when thus secured together as by adhesive, will form the pistol shown in perspective in FIG. 1. The two semi-circular depressions 14, 14a form a circular opening for a rubber stopper 20. When it is desired to fill the pistol, the stopper is removed, as is well known in the art, the stopper being replaced when the pistol is to be used.

The two semi-circular openings 15 and 15a form a circular opening for the sleeve portion 21 of a standard trigger-actuated pump 22, it being obvious that the pump 22 is put into position as shown in FIG. 2 just prior to the assembly of the two halves 10 and 11. No detailed showing of the pump 22 or the trigger is made because the pump is standard in the industry, and the trigger is of usual form.

Upstanding ribs 25 and 26 are formed on the interior surface of the part 10. These ribs 25 and 26 extend into portions 27 and 28, as well as portions 29 and 30, so as to form a continuous surface that preferably lies in the same plane as the continuous surface 12. The part 11 has ribs 25a and 26a together with surfaces 27a and 28a. Ribs 25a and 26a extend into portions 29a and 30a. These ribs 25a—30a form a continuous surface which is in the same plane as the surface 12a. Obviously, when the two complementary halves 10 and 11 are assembled by adhesive at surfaces 12 and 12a, as earlier discussed, an interior passage P is formed by the placing together and adhering also of the continuous surfaces of the ribs 25, 26, 27, 28, 29 and 30, and the ribs 25a—30a. It is well to note that parts 30 and 30a are formed so as to receive the upper discharge end 22a of the pump 22 and to hold it in place so that the pump will supply fluid to passage P. Preferably also, the passage P terminates in a relatively large chamber C, the end of which is closed by a nozzle forming rib as hereinafter set forth.

As those skilled in the art will appreciate, operation of the pump 22 by a trigger (not shown) in the standard manner known in the art, will carry fluid from the handle portion of the pistol into the interior passage P. It will be obvious that any leakage in the interior passage P will permit fluid to flow back into the grip portion of the pistol, rather than outwardly of the pistol, as would be the case were the passage P formed with one portion thereof the peripheral surfaces 12 and 12a.

That end of the complementary part 10 forming the barrel of the pistol, has a relatively large integral rib 40 extending transversely thereof, as is best shown in FIGS. 4 and 6. This rib 40 is adapted to enter a groove 41 formed in the pistol part 11, also as is best shown in FIGS. 4 and 6. Because of the manner in which the rib 40 interlocks with the groove 41, a very firm assembly of the two pistol parts 10 and 11 occurs at the end of the barrel. By placing a nozzle 42 in the rib 40, means are

created for the ejection of water from the passage P and chamber C, as those skilled in the art will well appreciate. The large size of chamber C permits use of a large rib 40, thereby allowing considerable area between nozzle 42 and the edge of the rib 40 where adhesive is placed. This obviates the danger of adhesive entering the nozzle 42. It is thus seen that through the utilization of an integral portion of one of the parts 10 and 11, a very effective assembly of the pistol results, together with the forming of a very effective nozzle.

As is probably best seen in FIG. 7, taken together with FIG. 1, each of the parts 10 and 11 is formed with a depression 50 which is between the ribs 25 and 26, as well as ribs 25a and 26a. This results in a contraction of the passage P for the faster flow of water therethrough, while at the same time effecting the saving of considerable material. Similar depressions 55 are formed, as best shown in FIG. 5, in alignment with ribs 30 and 30a in order to obtain effective holding and positioning means for the upper end 22a of the pump 22 within passage P. It may be well at this point to indicate that the pump 22 is further supported by the grip portion of the pistol through lugs 56 and 57 formed respectively on the parts 10 and 11.

I believe that my invention and its very considerable merits over the prior art will now be understood by those skilled in the art.

I now claim:

1. A toy water pistol comprising:

- (a) a pair of opposed parts having each a peripheral surface, said peripheral surfaces being shaped so as to form a pistol having a barrel portion and a grip portion, and adhesively secured to one another,
- (b) a transverse rib formed at the end of the barrel forming portion of one part and having an arc-shaped peripheral edge extending into a transverse arc-shaped slot in the barrel forming portion of the other part for closing the barrel end of said pistol, and
- (c) said rib having a small opening through which water may be ejected from said barrel.

2. A toy water pistol comprising:

- (a) a pair of opposed parts having each a peripheral surface, said peripheral surfaces being shaped so as to form a pistol having a barrel portion and a grip portion, and adhesively secured to one another,
- (b) a pair of spaced upstanding ribs on each of the interior surfaces of those portions of said parts forming the barrel of said pistol, said ribs contacting when said peripheral surfaces are adhered whereby to define by said ribs a passage for the movement of water through said barrel, and
- (c) said ribs being spaced from said peripheral surfaces so that fluid escaping from said passage flows into the interior of the pistol and into the grip portion thereof.

3. A toy water pistol comprising:

- (a) a pair of opposed parts having each a peripheral surface, said peripheral surfaces being adapted for adhesive application to one another to form a pistol having a barrel portion and a grip portion,
- (b) upstanding ribs on each of the interior surfaces of those portions of said parts forming the barrel of said pistol, said ribs contacting when said peripheral surfaces are adhered whereby to define therebetween a passage for the movement of water through said barrel,
- (c) said ribs being spaced from said peripheral surfaces so that fluid escaping from said passage flows into the interior of the pistol and into the grip portion thereof,
- (d) a transverse rib formed at the end of the barrel forming portion of one part and having an arc-shaped peripheral edge movable into a transverse arc-shaped slot in the barrel forming portion of the

other part for closing the barrel end of said pistol, and

(e) said rib having a small opening through which water may be ejected from said barrel.

4. A toy water pistol comprising:

- (a) a pair of opposed parts having each a peripheral surface that is continuous except at predetermined points, said peripheral surfaces being adapted for adhesive application to one another where continuous so as to form a pistol having a barrel portion and a grip portion,

(b) upstanding ribs on the interior surface of that portion of each of said parts forming the barrel of said pistol, said ribs on one part being adapted for contact with the ribs of the other part when said peripheral surfaces are adhered, and said ribs defining therebetween a closed passage for the movement of water through said barrel together with surfaces at the intake end of the passage for receiving the pressure end of a trigger-actuated pump supplying water to said passage,

(c) a thin transverse rib integral with the end of the barrel forming portion of one of said parts movable into a transverse slot formed in the barrel forming portion of the other of said parts for closing the discharge end of said passage, and

(d) said rib having a small opening through which water may be ejected from said passage.

5. A toy water pistol comprising:

- (a) a pair of opposed parts having each a peripheral surface that is continuous except at predetermined points, said peripheral surfaces being shaped so as to form a pistol having a barrel portion and a grip portion, and adhesively secured to one another,

(b) a pair of spaced upstanding ribs on the interior surface of that portion of each of said parts forming the barrel of said pistol, said spaced ribs on one part being adapted for contact with the spaced ribs of the other part when said peripheral surfaces are adhered, and said ribs defining therebetween a closed passage for the movement of water through said barrel together with the surfaces at the intake end of the passage for receiving the pressure end of a trigger-actuated pump supplying water to said passage, and

(c) said ribs being spaced from said peripheral surfaces so that fluid escaping from said passage formed by said ribs flows into the interior of the pistol and into the grip portion thereof.

6. A toy water pistol comprising:

- (a) pair of opposed parts having each a peripheral surface, said peripheral surfaces being adapted for adhesive application to one another to form a pistol having a barrel portion and a grip portion,

(b) upstanding ribs on the interior surface of that portion of each of said parts forming the barrel of said pistol, said ribs on one part being adapted for contact with the ribs of the other part when said peripheral surfaces are adhered, said ribs defining therebetween a closed passage for the movement of water from a trigger-actuated pump in communication with the intake end of the passage,

(c) said passage terminating in a relatively large discharge chamber at the end of the barrel of said pistol,

(d) a relatively large thin transverse rib integral with the end of the barrel forming portion of one of said opposed parts having an edge movable into a transverse slot formed in the barrel forming portion of the other of said parts for closing said relatively large chamber, and

(e) said rib having a small discharge opening positioned centrally thereof at a maximum distance from the edge entering the slot whereby water may be ejected from said passage.

7. A toy water pistol comprising:

- (a) a pair of opposed parts having each a peripheral

- surface, said peripheral surfaces being shaped so as to form a pistol having a barrel portion and a grip portion, and adhesively secured to one another,
- (b) co-operating passage-forming surfaces formed on the interior surfaces of those portions of said parts forming the barrel of said pistol, said co-operating passage-forming surfaces defining therebetween a passage for the movement of water through said barrel,
- (c) said co-operating passage-forming surfaces being spaced from said peripheral surfaces so that said passage is interior of said barrel portion whereby fluid escaping from said passage flows into the barrel portion of said pistol exterior of said passage and then to the grip portion,
- (d) trigger operated pump means for effecting flow of fluid from the grip portion into said passage, and
- (e) means forming a nozzle for the end of said passage through which water is expelled.
8. A toy water pistol comprising:
- (a) a pair of opposed parts having each a peripheral surface, said peripheral surfaces being shaped so as to form a pistol having a barrel portion and a grip portion, and adhesively secured to one another,
- (b) the interior surfaces of those portions of said parts forming the barrel of said pistol having passage-forming surface portions shaped for engagement when said peripheral surfaces are adhered whereby to form by said engagement a passage for the movement of water through said barrel, a trigger actuated pump within said grip portion connected to said passage for moving water into said passage from said grip portion,
- (c) said passage-forming surface portions being spaced from said peripheral surfaces whereby said passage is interior of said barrel portion and spaced from said

5

- peripheral surfaces so that fluid escaping from said passage flows into the interior of the pistol and into the grip portion thereof, and
- (d) a nozzle for the outer end of said passage through which water is expelled from said passage by operation of said trigger actuated pump.
9. A toy water pistol comprising:
- (a) pair of opposed parts having each a peripheral surface, said peripheral surfaces being shaped so as to form a pistol having a barrel portion and a grip portion, and adhesively secured to one another,
- (b) co-operating passage-forming surfaces integrally formed on the interior surfaces of those portions of said parts forming the barrel of said pistol, said co-operating passage forming surfaces defining therebetween a passage for the movement of water through said barrel, when said parts are adhesively secured,
- (c) said co-operating passage-forming surfaces being spaced from said peripheral surfaces so that said passage is interior of said barrel portion whereby fluid escaping from said passage flows into the barrel portion exterior of said passage and to the grip portion of said toy pistol, and
- (d) means for effecting flow of fluid from the grip portion into said passage.
